CLAIM

The ornamental design for a table, as shown and described.

DESCRIPTION

FIG. 1 is an isometric view of the table showing my new design incorporated in an end table;

FIG. 2 is a front elevational view of the table of FIG. 1 at a reduced scale; and

FIG. 3 is an end elevational view of the table of FIG. 2. The end and side of the table, not shown, are mirror images of the respective end and side shown.

FIG-1FIG-2FIG-3
